SOUND REPRODUCER.

Application filed May 16, 1922. Serial No. 561,415.

This invention relates to a device for reproducing sound transmitted electro-magnetically. The device is especially useful in connection with radio telephony and may be advantageously employed to amplify as well as reproduce the sound transmitted. The general object of the invention is to provide simple and effective mechanism operable by electromagnetic impulses to 10 produce sound without distortion irrespective of the amplification of the current variations transmitted.

The prior devices for reproducing sound now in use in radio telephony are of three 15 general types, each of which has disadvantages which it is the object of our invention to overcome.

The first type comprises a simple telephone receiver wherein there is an iron diaphragm acting as an armature for a permanent magnet which is strengthened and weakened by the electric current. Such devices result in distortion of the sound whenever the power is great enough to operate 20 with a horn, for the reason that the diaphragm must have such amplitude that at different times it is at materially varying distances from the pole pieces, so that a given magnetic strength has varying action 25 upon it, the result of which is that a constant power input causes a variable sound output, depending on the distances between the poles and the diaphragm.

A second type of reproducer in use employs an intermediately pivoted armature 30 operating between two pairs of poles, the poles of like sign being on the same side of the armature but being spaced to stand on opposite sides of the pivot, and there being a winding, the current through which strengthens one of the north poles and the diagonally opposite south pole, and at the same time weakens the other north pole and the diagonally opposite south pole. The armature being linked to a suitable diaphragm 40 reproduces the sound, but here again distortion occurs if there is a wide range of power input, for instead of continuing to act in the same manner, the impressed field in such circumstances becomes greater 45 than the permanent field and acts in the opposite direction so that a north pole for instance, instead of becoming simply a weaker north pole becomes a south pole. This

causes poor reproduction of sound when increased volume is attempted. 55

The third type of amplifying reproducer now in use, employs an electro-magnetic field which is supplied from outside source of electrical power and within this field is 60 located a moving coil which connects with the diaphragm. A disadvantage of this type of construction resides in the necessity for making electric connection with the coil, which must be free to vibrate according to 65 the telephone currents.

Our reproducer is designed to eliminate the most of the disadvantages of the foregoing types of reproducers and at the same time maintain a high efficiency. In accomplishing this we have provided a device 70 which avoids the employment of permanent magnets and avoids any electric connection with the movable element. Broadly, the device comprises the employment with a diaphragm of a coil, an energized circuit therefor, and an electronic valve for controlling the flow of current in the winding. We prefer to employ for this purpose two iron-clad solenoids suitably spaced and mounted end 75 to end in a rigid holder, and we utilize the movement of an armature lever either by direct connection with a phonograph diaphragm or by a multiplying connection therewith, as desired. 80

We may provide simply a holder carrying a large diaphragm and a link from the armature lever directly to the center of the diaphragm, or we may use a small diaphragm and multiplying leverage between it 85 and the armature lever. The second preferred method and one productive of highly desirable results with great simplicity and convenience may be readily effected by using an ordinary phonograph reproducer, the 90 needle of which rests on the armature lever. In such case it is entirely feasible to simply stand our solenoid unit within the ordinary phonograph cabinet at the side of the rotary table, with the armature projecting upwardly and with its movement in a path approximately radial of the rotary table, the reproducing needle being rested on the top 95 of the armature lever. The armature lever thus gives to the phonograph needle the lateral movements corresponding to those ordinarily given by the groove in the disk record, and the sound is emitted through the 100 105

phonograph horn. Our invention includes broadly this method of utilizing armature vibrations however produced, as well as the means we have invented for producing such vibrations.

Our invention is illustrated in the drawings hereof and is hereinafter fully described and the essential features are summarized in the claims.

- 10 In the drawings, Fig. 1 is a front elevation of our reproducing and amplifying device or "loud speaker" of a form employing the large diaphragm in direct connection with the armature; Fig. 2 is a vertical section through such device; Fig. 3 is a vertical section on a larger scale through the solenoid mechanism along the axis thereof, being in a plane parallel with Fig. 2; Fig. 4 is an end view of the solenoid mechanism; 15 Fig. 5 is a detail illustrating means which may be employed for clamping the diaphragm to the holder body; Fig. 6 is an elevation of the combination of our solenoid mechanism with the phonograph reproducer 20 and sound arm, the solenoid mechanism being shown in end view with its casing sectioned; Fig. 7 is an enlarged view of the solenoid mechanism arranged for this adaptation in side elevation; Fig. 8 is a diagram of the circuits, tubes, batteries, etc., 25 employed in energizing the solenoids.

As shown in Fig. 3, 10, 10 indicate two solenoid windings, each suitably ironclad, as for instance between iron cups 11 and the 30 iron disks 12 screwed therein to entirely house the coil. Each disk 12 carries an adjustable plug 13 mounted in the disk and projecting into the solenoid opening. This plug is formed so that it may be conveniently 35 adjusted as by being threaded in the disk 12 and having a screw driver slot 14 in its end and carrying a jam nut 15 engaging the face of the disk 12.

The two ironclad solenoids are rigidly 40 carried opposite each other as shown in Fig. 3. To effect this we have shown each iron cup 11 as threaded at its inner end and as screwing into a non-magnetic ring 20. Suitably carried by the non-magnetic ring 20 in 45 a position equi-distant between the solenoids is the armature lever 30 which is shown as carried by a leaf spring 31 mounted in the screw 32 adjustably clamped by nuts 33 and 34 to the ring 20. This armature lever 30 50 carries magnetic cores 35 extending in opposite directions therefrom and entering the solenoid openings respectively through sufficiently large openings in the ironclad cups 55 so that the cores will be out of contact there- 60 with.

It will be seen that with such a construction as described, if the current through one solenoid is strengthened, another through the other solenoid weakened, by the action 65 of suitable electric valves, an incoming al-

ternating current may thus cause a vibration of the armature lever 30 corresponding to the frequency and wave form of the incoming current. The armature lever 30 is connected in a suitable manner with a suitable 70 diaphragm to give a corresponding sound reproduction.

As illustrated in Figs. 1, 2 and 5, 40 indicates a suitable holder for a comparatively large diaphragm 41 which is connected by 75 a link 42 with the armature lever 30. The holder is shown as a dish shaped metal member provided with suitable supporting legs 45, though other form of holder may be employed as desired. As shown the dish-shaped member 40 has an outstanding peripheral flange 46 to which is fastened an inwardly flanged ring 50. This ring is L-shaped in cross section and bears at its outer portion against the edge of the flange 46 85 while its inner portion overhangs the diaphragm 41. Suitable screws 52 passing through the ring and into the flange 46 serve to cause the ring to clamp the diaphragm to the flange. A pair of gaskets 53 and 54 90 lie on opposite sides of the diaphragm and thus enable its edge to be effectively clamped in place in a sufficiently yielding manner to allow proper vibration thereof, as will be readily understood.

In the loud speaker shown in Figs. 1 and 2, the solenoid mechanism may be readily held in place by means of a pair of angle brackets 55 secured to opposite sides of the ring 20 and secured also to the back portion of the body 40. Suitable wires for energizing the solenoids, (one for each solenoid and a common return), may pass into the device in the form of a cable 58, as illustrated in Fig. 2, and may be connected to 100 binding posts 57 insulatingly mounted on the ring 20.

In cases where it is desired to use the solenoid mechanism to vibrate the phonograph needle, a suitable supporting base is 110 provided instead of the brackets 55 extending beyond the end of the device. Such base may conveniently be a sheet metal strip 60 fastened to the underside of the ring 20 and extending in each direction and turned 115 downwardly in the form of supporting legs 61 as shown in Figs. 6 and 7. For such an installation as this it is desirable to provide a casing about the solenoid mechanism. Such casing is illustrated at 65. It may be 120 readily made of sheet metal or similar material and house the device and be secured to the down-turned legs 61 thereof as shown. The casing has a suitable hole 67 at its top through which projects the armature lever 125 30. The end of the lever in this case is preferably made with a suitable indentation, in which the needle of the phonograph may be placed.

In order that the needle or stylus may be 130

positively given the lateral movements corresponding to those ordinarily given by the groove of a phonograph disc record, as previously stated herein, this indentation may 5 advantageously receive the point of the needle to a suitable depth as indicated Fig. 7. This indentation is preferably in the nature of a sharp depression or groove into which the end of the needle projects, being held 10 there, by the weight of the pivoted portion of the usual reproducer mechanism, with the result that the vibrations of varying amplitude are correspondingly transmitted from the armature lever through the needle 15 to the phonograph diaphragm. However, if a sharp needle is used it has been found to make its own depression vibrating member, by the weight of the phonograph sound box such as to make a satisfactory connection. 20 It is also obvious that it may be readily removed and replaced in operating position on the record, by merely lifting the needle from the vibrating lever and placing it upon the record in the usual manner.

25 As shown in Figs. 6 and 7, 70 indicates a phonograph sound arm, 71 the reproducer box thereof carrying the diaphragm 72, and the reproducer lever 73 pivoted at 74. The screw 75 clamps the needle 76 in the usual manner. Our device may simply rest by gravity on the stationary phonograph table 79, being placed at the side of the rotating table in a convenient position with the axis 30 of the solenoid device extending substantially radially of the rotating table. The device is comparatively small and the movement allowed to the reproducer box and the sound arm enables the reproducer needle to be placed on the end of the armature lever without any change whatsoever in the 35 phonograph arrangements.

We will now describe the means by which the illustrated variable current impulses into solenoid variations of the same frequency 40 to cause impulses may be translated in one direction to strengthen one solenoid and at the same time weaken the other solenoid and those in the other direction to effect the reverse result, it being understood that such translating means is identical whether the armature lever be directly connected with the diaphragm or operate the phonograph needle or utilize its vibrations in another manner. It will also be understood that in 45 making this novel arrangement of a magnetic device with a vibrating member coacting with the usual reproducer mechanism of a phonograph, in the manner described, is not limited to the precise arrangement 50 shown and described herein for translating the variable current into mechanical vibrations.

In the diagram, Fig. 8, 80 indicates a suitable transformer which as shown, has a pri-

mary 81 and a secondary 82, though if desired an autotransformer may be employed having a winding corresponding to such secondary, or in fact any suitable device may be used for coupling the output conductors 83 with the input portion of our translating system. 84^a and 84^b designate a pair of electron valves in the form of vacuum tubes of the usual filament, grid and plate type familiar in radio reproductions. 86 designates a rheostat for controlling the filament of the two tubes. A, B and C indicate suitable batteries.

The circuits in the diagram may be traced as follows: From the grid 87^a of the tube 84^a a conductor 90 extends to one end of the secondary 82, while a conductor 91 extends from the other end of the secondary to the grid 87^b of the tube 84^b. A line 93 extends from the plate 88^a of the tube 84^a to the solenoids 10^a and a line 94 extends from the plate 88^b of the tube 84^b to the other solenoid 10^b. 95 indicates a common return from the two solenoids, which is connected to the plus side to the B battery. The minus side of the B battery is connected by a line 96 which branches and passes to the two filaments 89^a and 89^b, respectively. 97 indicates the common return from the two filaments which is connected to the filament rheostat 86. From the rheostat a line 98 leads to the plus side of the A battery, which is connected on its other side to the line 96. Another connection from this line 96 leads to the plus side of the C battery, and from the other side of this battery a line 99 leads to the center of the secondary transformer winding 82.

The controlling members of the electron valves are the grids. By causing the voltages on the grids to fluctuate in respect to the filament voltage, the plate currents from the B battery which flow in the coils of reproducer will fluctuate correspondingly. If the grid 87^a of the tube 84^a is more positive 105 than the filament (heated by the A battery) then the current in the coil 10^a will be stronger than normal. If, however, the grid 87^a has a voltage which is negative in respect to the filament, it will cause the plate current in the same coil to diminish below normal value.

According to the diagram of connections shown the input transformer has its winding tapped in a way that if grid 87^a becomes more positive than the normal value then grid 87^b must necessarily become negative to the same extent, and vice versa. Thus, if a feeble telephone current be caused to flow in the coupling transformer, the result will be a fluctuation of the voltages on the two grids in such a manner that for any instant when the voltages on either grid becomes more positive than the normal then

simultaneously the voltage on the other grid will become correspondingly more negative than normal.

The C battery is used for the purpose of fixing the normal voltage on both grids to a definite value in respect to the filament voltage, in order to allow the valves to operate on the proper part of their characteristic curves.

10 Since the action of the electron valve is such that when the grid voltage becomes more positive, the plate current increases and when the grid voltage becomes more negative the plate current decreases, the action of the reproducer is as follows:

The mechanical pull on the armature lever is determined by the strength of the currents in the windings of the solenoid coils. Under normal conditions when no telephone currents enter the device the voltages on the grids of the two electron valves are the same and can be stated to have the normal value. This will result in the two plate currents having practically equal strength, and, for 25 this reason the magnetic pulls from the two opposing coils which are connected into these plate circuits will be equal and will balance each other, causing no motion of the connecting lever or diaphragm.

30 With an audio-frequency current entering the system, the grid voltages will fluctuate in opposite directions from the normal at the same frequency. This will cause a similar unbalance of the plate currents and consequently a similar unbalance of the magnetic pulls from the coils. The result will be a mechanical movement of the connecting lever in the direction of the coil having the current which is greater than normal. When 35 the incoming telephonic current flows for an instant in the opposite direction the resultant effect on the lever will be in the opposite direction. In this manner it can be seen that a varying current of audio-frequency will cause an alternating motion of the lever, which will have the same frequency and wave form. Accordingly, a telephonic current in the secondary of the coupling transformer, will cause the lever to follow the 40 same variations, and in this manner, produce the desired sound when the vibrating lever is connected to a sound producing diaphragm.

It should be noted that while the employment of two coils and two electron valves in the translating circuit is desirable, results could be obtained by omitting one coil and its valve and relying on a suitable spring (for instance the spring supporting the armature lever) to counteract the used coil. Such construction is intended to be included within the claims of this invention.

We claim:

1. The combination with a phonograph reproducer having the usual actuating lever

and stylus, of a pair of iron clad solenoids positioned in axial alignment and spaced apart, a lever mounted between said solenoids and carrying cores for the respective solenoids and having a depression to receive 70 said stylus, a frame in which said parts are mounted to make a unit adapted to stand on a suitable support.

2. In combination with a phonograph arm, reproducer and needle, of a self-contained unitary electro-magnetic vibrator comprising a pair of electro-magnetic coils positioned end to end and spaced apart, and an armature lever mounted between said coils and extending toward the phonograph 75 reproducer in a plane parallel with the diaphragm thereof and having means for directly engaging the needle to vibrate it transversely of the plane of the reproducer diaphragm.

3. A sound reproducing device including an electro-magnetic means having a vibrating member, spaced apart magnetic poles adjacent to said vibrating member, an electro-magnetic means for causing audio frequency variations in an electric circuit to actuate the vibrating member, a phonograph reproducer including a diaphragm and actuating lever member, means for making an operative connection including a depression on one of said members and a co-acting projection carried by the other of said members.

4. A sound reproducer as claimed in claim 3 characterized in that the vibrating member 100 is a reed secured at one end and the magnetic device including a coil adjacent to the reed to cause vibration thereof by variable magnetization.

5. A sound reproducing device consisting 105 of a phonograph reproducer having the usual diaphragm and stylus, a vibrating armature reed having means for receiving and engaging said stylus, means for resiliently mounting said reed uprightly and 110 magnetic means for vibrating the reed substantially at right angles to the plane of the phonograph diaphragm.

6. The combination with a phonograph reproducer and tone arm with the usual 115 stylus for actuating the diaphragm, of an electro-magnetic means, including a vibrating reed and a mounting therefor such that the reed projects upwardly, said reed having a depression for receiving the end of the 120 needle and which is held in position by the weight of the reproducer, while the said mounting rests upon a phonograph cabinet or record plate.

7. The combination of a phonograph tone 125 arm having a reproducer box; an actuating lever for the reproducer box, a magnetic device having a vertically mounted vibrating member adapted to have the weight of the 130 reproducer box resting thereon and having a 135

- depression forming opposed shoulders to receive and to operate the lever, said lever being readily removable but being engaged by the opposed shoulders to cause positive vibration of the lever in two directions of movement of the vibrating member whereby the vibratory motion of the vertically mounted member may be transmitted through said connection in positive and certain synchronism in the usual plane of vibration of said actuating lever.
8. The combination of a phonograph tone arm having a reproducer box, diaphragm, actuating lever and stylus needle, and a magnetic device having a resiliently mounted vibrating member projecting upwardly and having an upper surface adapted to receive the point of the stylus and means for causing the said member to vibrate transversely relative to said diaphragm, whereby the weight of the reproducer box may cause a positive actuation of the needle when resting upon said member.
9. The combination of a phonograph tone arm, mounted to swing horizontally and having its reproducer box mechanism, including the usual actuating lever pivoted to move vertically, a magnetic device having a resiliently mounted vibrating member adapted to have the weight of said pivoted portion of the tone arm rest thereon, and means connecting said vibrating member and said lever for positively transmitting said vibration in both directions to the phonograph diaphragm and transversely thereof, said connection being readily separable by raising the reproducer box mechanism.
10. In combination a swingable phonograph tone arm, a reproducer mechanism mounted on the end of the arm and having an actuating lever and phonograph stylus, a magnetic device having a vibrating member provided with a depression for receiving said stylus and presenting shoulders preventing swinging of the tone arm when the stylus rests therein, means for actuating the vibrating member transversely of the plane of the reproducer mechanism whereby the inertia of the reproducer causes the vibration to be transmitted through the stylus to the diaphragm.

In testimony whereof we hereunto affix our signatures.

FRANK J. KAEHNI.
WILLIAM L. KAEHNI.
